UNITED STATES PATENT OFFICE.

THOMAS L. STONE, OF NEWARK, NEW JERSEY, ASSIGNOR TO HAMPDEN GLAZED PAPER & CARD COMPANY, OF HOLYOKE, MASSACHUSETTS, A CORPORATION OF MASSACHUSETTS.

DESIGN FOR COVER PAPER OR THE LIKE.

Application filed August 15, 1927. Serial No. 23,091. Term of patent 14 years.

To all whom it may concern:

Be it known that I, THOMAS L. STONE, a citizen of the United States, residing at Newark, in the county of Essex and State of New Jersey, have invented a new, original, and ornamental Design for Cover Paper or the like, of which the following is a specification, reference being had to the accompanying drawing, forming a part thereof. The figure is a plan view of a piece of cover paper or the like embodying my new design.

I claim the ornamental design for cover paper or the like as shown.

THOMAS L. STONE.
